UNITED STATES PATENT OFFICE.

LEWIS MARTIN TUCKER AND PERCY W. HATFIELD, OF WAKEFIELD, MASSACHUSETTS,
ASSIGNORS TO WILLCOX & GIBBS SEWING MACHINE CO., OF NEW YORK, N. Y., A
CORPORATION OF NEW YORK.

PULL-OFF MEANS FOR SEWING MACHINES.

Application filed October 31, 1919. Serial No. 334,727.

To all whom it may concern:

Be it known that we, LEWIS MARTIN TUCKER and PERCY W. HATFIELD, citizens of the United States of America, and residents of Wakefield, Massachusetts, have invented new and useful Improvements in Pull-Off Means for Sewing Machines, which invention is fully set forth in the following specification.

10 This invention relates to thread pull-off means for sewing machines. Although designed especially for use with the machine known commercially as the Willcox & Gibbs Sewing Machine Company's "Flatlock Machine," shown, for example, in the patent to A. A. Merritt, No. 1,041,652, dated October 15, 1912, the pull-off means of this invention are not restricted to use with any particular type or make of sewing machine.

20 In forming a so-called interior seam, such as those on the sides of ladies' underwear begun at a point relatively distant from the edge of the material, it is important that the formation of perfect stitches should begin with the very first stroke of the needles, because missed or imperfect stitches, even at the start of such a seam, result in marred appearance and defective work. In forming such interior seams with the aforesaid

30 flatlock machine, some operatives have experienced missed or malformed stitches at the beginning of the seam. The probable cause is that in starting or preparing to start the seam, the somewhat lengthy thread-ends ordinarily left at the finish of a preceding operation are gotten into such position as to be severed by the blades of the trimmer mechanism, thus leaving only short lengths of the needle-threads beyond the

40 eyes of the needles inadequate to enable the pressure of the presser-foot to grip and anchor said thread-ends against the back-pull imposed thereon as the needles descend to pull more needle-thread through the tensions and form needle-thread loops through the work to be entered by the loopers. Such failure to hold the needle-thread ends, and the consequent failure to form needle-thread loops for the looper-threads, result in one or 50 more missed or imperfect stitches before the formation of perfect stitches begins.

The principal object of this invention is the provision of automatically operating pull-off means which will overcome the

aforesaid difficulties by forming slack in the 55 needle-threads between the tension means and the eyes of the needles sufficient to accommodate the down-stroke of the needles in beginning a seam without imposing back-pull sufficient to draw the relatively short 60 needle-thread ends down through the work. The aforesaid and other objects and advantages attained by the invention will be more fully understood from the following detailed 65 explanation with reference to the accompanying drawing illustrating what is now believed to be the preferred embodiment of the invention as applied to a machine of the character of the aforesaid flatlock machine.

In said drawing—

70 Fig. 1 is a plan view of a portion of a sewing machine with the pull-off means of this invention applied thereto;

Fig. 2 is a perspective view of a group 75 of the mechanism shown in Fig. 1; and

Fig. 3 is a perspective view of some of the parts.

The drawing will first be explained in so far as it illustrates structure of the aforesaid commercial flatlock machine, such 80 structure (except for minor differences) corresponding to that illustrated in the aforesaid Merritt Patent No. 1,041,652, and particularly in Figs. 49, 50 and 51 thereof.

5 is a portion of the hollow bridge and 6 a portion of the hollow left-hand standard of the machine-frame. 7 is a rotary take-up for the four needle-threads *a*, *b*, *c*, *d*, and 8 a rotary take-up for the four looper-threads *e*, *f*, *g* and *h*. 9 is the looper-thread 90 tension-stand, secured to the top of the bridge 5 and having mounted thereon a thread-guide-plate 10 through converging passages of which the looper-threads pass to four sets of tension-plates 11, from which latter said threads pass through guide hooks 12 and thence over rotary take-up 8. A bar 13, sliding freely in a passage through the base of stand 9, has secured thereon an upwardly extending arm 14 which in turn 100 is secured to the end of a rod 15 (parallel to bar 13) which also slides freely in a bearing in the stand 9. Rod 15 passes through all of the tension-plates 11 and is encircled by a spring 16, the tension of which, in pressing the tension-plates together, is adjustable by turning nut 17 screw-threaded onto the end of rod 15.

20 is the needle-thread tension-stand secured to the top of bridge 5 at the left-hand end thereof and having mounted thereon a thread-guide-plate 21 through converging 5 passages of which the four needle-threads pass to four sets of tension-plates 22 and thence through guide-hooks 23 and over rotary take-up 7. Bar 13 also slides freely in an opening through the base of stand 20. 10 An arm 24 secured to bar 13 is fixed to the ends of rods 25 and 26 which slide freely in bearing openings in stand 20. Rod 25 passes through the tension-plates 22 and is encircled by a spring 27, the tension of which, 15 in pressing the plates together, is adjustable by a nut 28 on the end of rod 25. Rod 26 is encircled by a spring 29, passes through tension-disks 30 and has on its end a nut 31 for adjusting the tension of said spring in 20 pressing said disks together. The tension-disks 30 and a thread-guide 32 are for a cross-thread, not shown. A spring 33 encircling the end of bar 13 bears at one end against arm 24 and at its other end in a 25 socket (dotted lines Fig. 1) in the end of stand 20, and is of sufficient tension to normally force the bar 13 and all of its connections to the left until the stop-pin 34 through bar 13 abuts the end of the base of stand 30 20 (see Fig. 2 and dotted lines Fig. 1), such being the normal position of the parts when the thread-tensioning means are exerting tension upon the threads. As shown in Fig. 35 1, the upright plate forming part of the thread-stand 20, at its left-hand end, fits over an opening 35 in the upright wall in the hollow standard 6 of the machine-frame, with the end of bar 13 projecting into the interior of said hollow standard where it can 40 be engaged by the beveled or cammed upper end of an arm 36 secured to a rock-shaft 37. When the presser-foot (not shown) is lifted, the shaft 37 is rocked, by connections such as shown in Fig. 4 of the aforesaid Merritt 45 patent, moving arm 36 from the position shown in dotted lines to that shown in full lines in Fig. 1, thereby moving bar 13 (and all of its connections) to the right against the tension of spring 33 and releasing all 50 of the thread-tensioning means.

Coming now to an explanation of the pull-off means of the present invention, a plate 40 has an opening 41 through which bar 13 passes. To provide for securing said plate 55 on the bar in any desired position of adjustment lengthwise of the bar, a slot 42 is formed to intersect opening 41, thereby providing two opposing members which may be drawn together by a screw 43 to contract the opening 41 about the bar 13 and thereby clamp the plate in any desired position on the bar. A bell-crank lever 44 is pivoted to plate 40 by a screw-stud 45. A link 46 is pivotally connected to an arm of lever 44 by a screw- 60 stud 47, said link at its other end being 65

pivotedly anchored to a screw-stud 48, which may be one of three screws employed in securing the tension-stand 9 in place. Screw-stud 47 may engage any one of the threaded openings 51 of lever 44 to vary or adjust the 70 movement imparted to said lever. The other arm of lever 44 has an upturned end provided with an opening to receive a thread-engaging member 49 and with a set-screw 50 to secure said member in any desired position 75 of adjustment. Member 49 is preferably made of stiff wire bent in the peculiar way illustrated to form an elongated slot 52 through which the four needle-threads pass after they leave the tension-plates 22 and before they engage the hooks 23. 80

In operation, when the arm 36 is in the dotted line position, Fig. 1, clear of the end of bar 13 (a position to which said bar is automatically moved by lowering of the presser-foot, as shown by the aforesaid Merritt patent), spring 33 moves bar 13 to the left until arrested by stop-pin 34, and through the rods connected to bar 13 throws all of the tension means into action to impose tension upon the threads, and brings the thread pull-off means to the position shown in dotted lines in Fig. 1. When the sewing machine presser-foot is lifted at the end of a seaming operation, arm 36 is thereby moved to its full-line position Fig. 1, moving bar 13 and its connections to the right against the pressure of spring 33 and releasing all of the thread-tensioning means. In such movement, bar 13 also moves the 100 pull-off means to the position shown in full lines, Fig. 1, such movement including swinging of lever 44 about its pivot-stud 45, whereby thread-engaging member 49 pulls the four needle-threads out to the position 105 shown in full lines, Fig. 1. When, at the beginning of another seaming operation, the presser-foot is lowered, the arm 36 thereby shifted to its dotted line position, the rod 13 actuated by spring 33 to again bring the thread-tension means into action, and the thread pull-off means moved to the dotted line position thereof, Fig. 1,—such movement of the thread pull-off member 49 slacks the needle-threads to the amount of 110 thread pulled past the tension-plates 22 by the previous movement of member 49 to its full line position of Fig. 1. When the needles make their first downward movement, say in beginning an interior seam such as hereinbefore mentioned, and with 115 only short thread-ends through the needle-eyes and in the grip of the presser-foot, the aforesaid slack in the needle-threads is sufficient to accommodate the full movement of 120 the needles, thereby relieving the needle-threads of back-pull (such as would be incident to pulling more thread past the tension means) sufficient to draw the ends thereof 125 downward through the work and result in 130

missed or malformed stitches at the beginning of the seam.

The invention may be used for one or more threads and is not limited to embodiment in the particular form illustrated and described, as other embodiments may be made without departing from the spirit and principle thereof.

What is claimed is:-

10 1. In a sewing machine, the combination with a longitudinally movable part thereof to which movement is imparted upon raising and lowering of the presser-foot to engage work thereunder, of pull-off means operable upon one or more stitch-forming threads and attached to and actuated by longitudinal movement of said first-named part.

2. In a sewing machine, the combination with needle-thread tensioning means and a movable part to which longitudinal movement is imparted upon raising and lowering of the presser-foot to engage work there-

under, of pull-off means attached to and actuated by longitudinal movement of said part to draw needle thread past the tensioning means and provide slack therein available to the needle or needles in subsequent operation thereof.

3. In a sewing machine, the combination with needle-thread tensioning means and a movable part of the machine to which longitudinal movement is imparted upon raising and lowering of the presser-foot to engage work thereunder, of a pull-off member pivotally attached to and actuated by longitudinal movement of said machine part to make pivotal movement and thereby draw needle thread past the tensioning means and provide slack in the thread available to the needle or needles in subsequent operation thereof.

In testimony whereof we have signed this specification.

L. MARTIN TUCKER.
PERCY W. HATFIELD.
